D. L. GARDNER

Des. 92,896

CASKET

Filed May 21, 1934

UNITED STATES PATENT OFFICE

92,896

DESIGN FOR A CASKET

Dozier L. Gardner, St. Louis, Mo., assignor to St. Louis Casket Company, St. Louis, Mo.

Application May 21, 1934, Serial No. 51,876

Term of patent 3½ years

To all whom it may concern:

Be it known, that I, DOZIER L. GARDNER, a citizen of the United States, residing at St. Louis, in the State of Missouri, have invented a new, original and ornamental Design for a Casket, as shown in the accompanying drawings and described in the following specification.

In the drawings:

I claim:

The ornamental design for a casket as shown.

DOZIER L. GARDNER.
